SPOON OR SIMILAR ARTICLE

Frank R. Perry, Oneida, N. Y., assignor to Empire Crafts Corporation, Newark, N. Y., a corporation of New York

Application April 1, 1958, Serial No. 50,278

Term of patent 14 years

(Cl. D54—12)

Fig. 1 is a front elevational view of a spoon showing my new design;

Fig. 2 is a side elevational view of the spoon;

Fig. 3 is a rear elevational view of the spoon; and

Figs. 4 and 5 are sections on the respective lines 4—4 and 5—5 of Fig. 1.

The essential features of my design for a spoon or similar article reside in the configuration of the handle in combination with the particular type of ornamentation as applied thereto.

I claim:

The ornamental design for a spoon or similar article, substantially as shown and described.
